UNITED STATES PATENT OFFICE.

ELEAZER KEMPSHALL, OF BOSTON, MASSACHUSETTS, ASSIGNOR TO THE KEMPSHALL MANUFACTURING COMPANY, A CORPORATION OF NEW JERSEY.

GOLF-BALL.

SPECIFICATION forming part of Letters Patent No. 697,422, dated April 8, 1902.

Application filed January 15, 1902. Serial No. 39,800. (No model.)

To all whom it may concern:

Be it known that I, ELEAZER KEMPSHALL, a citizen of the United States, residing in Boston, in the county of Suffolk and State of Massachusetts, have invented certain new and useful Improvements in Golf-Balls, of which the following is a specification.

This invention relates to balls such as used in golf and certain other games.

My present improvements relate chiefly to an improvement in the cover of the ball, whereby the same is rendered more efficient and durable.

In the drawings accompanying and forming part of this specification, Figure 1 is a view, partly broken away, of a ball made in accordance with my present improvements. Fig. 2 is a view of a jacketed inner ball incased with incompletely-cured celluloid. Fig. 3 illustrates a method of compressing a shell upon a ball, and Fig. 4 is a view of an elastic core.

Similar parts are designated by similar characters of reference in the several drawings.

The shell (designated at A, Fig. 1) may consist of celluloid, while the nucleus B may consist of any suitable material, such as rubber of suitable consistency or gutta-percha; but preferably I form the nucleus in this instance by winding rubber threads into the form of a ball, as at C, Fig. 4. I inclose this nucleus ball in an envelop consisting of one or more layers of elastic belting D, which may be woven of a suitable width—say three-quarters of an inch—or may be produced by cutting elastic webbing or fabric into strips. This elastic belting I put under tension while winding it around the nucleus, so that it firmly fits and compresses the core, whatever may be the substance or form of the latter, although the elastic belting is especially effective when the core is of the kind illustrated at Fig. 4. A characteristic of elastic belting when used for this purpose is that it draws right down into a spherical form or clings closely for its entire width to the core, thus not only holding the same under compression, but also making a practically smooth and uniform jacket or blanket around the

latter. In its original shape the inner ball is substantially round, although it may depart from the spherical form within the scope of the invention; but I prefer that its bulk shall be a little too large for the final capacity 55 of the shell.

Upon the belted core I place a cover of partially-cured celluloid, preferably in the form of hemispherical blanks E and F, which may be stuck upon the core by means of a solution of 60 celluloid. The preliminary ball thus formed and seen at Fig. 2 I inclose in hemispherical segments A' and A'', Fig. 3. The parts thus assembled are placed between forming-dies— 65 as, for instance, G and H—whereupon the latter are pressed together. The dies may be heated, so as to bring the material of the shell into suitable condition and consistency both for uniting the portions thereof and also for facilitating the compressing and shaping ac- 70 tion of the dies. The dies may be allowed to cool before the balls are taken out, so as to give the shells an opportunity to reharden, whereby they are enabled to retain their shape when removed. The abutting edges of the 75 outer segments at A'' may be made somewhat full, thereby to furnish material for properly forming the joint between them as they are subjected to the final compression. The fibrous portion of the jacket serves to prevent 80 the heat of the dies from escaping into the nucleus, whereby injury of the latter is prevented and whereby also the shells may be united without the employment of an undue amount of heat.

It will be understood that the layers of the shell are compressed between the dies and the resisting mass of the ball contained therein, and since said inner ball is first prepared somewhat oversize the resistance thereof 85 while under such compression furnishes a substantial support for sustaining the relatively thin shell against any desired pressure. The application of celluloid solution to the jacket of elastic belting permeates the fibers 90 of the latter, so that it becomes at the finishing operation firmly incorporated with the shell.

By the expedient of lining the outer shell layer with incompletely-cured celluloid I am 100

enabled to employ for said outer layer celluloid which is highly seasoned, and hence tough, durable, and well tempered, these qualities being enhanced because of the thinness of said layer, while the solvent present in the semicured lining is sufficient at the heating and compressing operation to permeate the outer shell and render the same plastic, the layers of celluloid adhering or welding together and becoming closely compacted under the pressure. In the finished shell the qualities of the thin and well-cured layer A are present, while the shell is also of sufficient thickness to enable it to fulfil the requirements of the ball. The layer E F not only aids in the molding of the outer layer, but also by reason of its greater plasticity serves to compensate for local irregularities in the form of both the outer shell and the inner ball, thinning out at points where the inner ball is close to the outer shell and also filling up any cavities that may be present, thus thoroughly uniting the outer shell-layer to the core and improving the qualities of the ball.

25 By reason of its elasticity the inner ball cooperates with the spring-shell, so as to restore the latter instantly to its normal shape after distortion by a blow. The efficiency of the filling for this purpose is greatly enhanced 30 by having it constantly under compression, since the expansive pressure thereof in all directions tends constantly to maintain a spherical shape of the shell.

From the foregoing it will be seen that the 35 finished ball comprises a relatively soft elastic nucleus, a relatively hard, springy, laminated shell, and an intermediate layer of tensioned elastic belting or fabric. This layer, it will be seen, forms a fibrous reinforcement 40 for the shell itself and is of great value, since the force of a blow is diffused, and hence the ball is generally altered from its true spherical shape, whereby the elasticity of the inner ball acts over a large area with greatly-increased 45 effectiveness. The usual tendency of a shell, especially when the latter is made of thin celluloid, is to dent in sharply, thus affecting only the part of the nucleus which is right behind the area of impact and affecting only a small 50 portion of the nucleus, so that only this small portion of the nucleus is effective in returning the shell to its original shape, whereas by placing a jacket of elastic fabric under tension over the nucleus sharp indentation of the 55 shell is prevented, since if the jacket is pushed inwardly anywhere a large area thereof is owing to its longitudinal tension necessarily affected and dragged inwardly to a slight extent, so that instead of a deep indentation 60 being produced in the nucleus over a small area the latter is slightly flattened over a large area, and thereby the entire shape of the nucleus as well as the shell is a little distorted, and in consequence the whole energy of 65 the imprisoned mass added to the natural resiliency of the elastic belting is called upon,

and the ball is restored instantly to its normal position. Moreover, said elastic belting to a material extent relieves the shell from the stress due to the outward or expanding pressure of the compressed elastic nucleus, so that the shell is less liable to deteriorate or crack and its life is greatly prolonged. In this connection it will be perceived that the compression of the inner ball at the finishing 75 operation does not materially reduce the longitudinal tension of the elastic belting at any part, so that the same is effective to restrain the nucleus after the ball is finished. Thus it will be seen that the elastic fabric forms 80 an excellent backing or base for the shell and that the extra plastic lining-blanks E and F serve to compensate for the irregularities of the belted core, so that at all points the shell is effectually joined to the core or to the 85 belting thereon.

In using the term "celluloid" I refer to celluloid or pyroxylin compounds generally and do not limit myself to any particular variety or grade or mixture.

The herein-described process is made the subject-matter of my pending application, Serial No. 94,006, filed February 14, 1902.

Other kinds of cores may be employed in connection with a celluloid shell having an 95 extra plastic lining.

Having described my invention, I claim—

1. A playing-ball comprising an elastic core and a celluloid shell, the exterior portion of the shell being well cured and the interior portion thereof being incompletely cured and compactly uniting the core directly to said exterior, and the shell being compacted upon the core and holding the same under compression.

2. A playing-ball comprising an elastic core and a shell built up of celluloid layers, the outer layer being thin and highly cured and compacted or welded upon the inner layer, and the latter being incompletely cured and 110 adhering to all portions of the surface of the core.

3. A playing-ball comprising an elastic core, and a shell compressed thereon; said shell comprising a highly seasoned or cured outer 115 layer of celluloid and a lining of incompletely-cured celluloid adjacent to the core.

4. A playing-ball comprising an elastic core enveloped or incased in fabric and celluloid, a portion of the celluloid upon the exterior 120 of the ball being highly cured, and an interior portion thereof being incompletely cured; and said fabric being embedded in the celluloid adjacent to the core.

5. A playing-ball comprising an elastic core 125 enveloped or incased in elastic belting and celluloid, a portion of the celluloid upon the exterior of the ball being highly cured, and an interior portion thereof being incompletely cured; and said elastic belting being embedded in the celluloid.

6. A playing-ball comprising a core of elas-

tic thread wound under tension; elastic belt-
ing enveloping said core; semiseasoned cellu-
loid segments incasing and incorporated with
said envelop; and segments of highly-sea-
5 soned celluloid incasing said semiseasoned
celluloid; said segments being welded to-
gether at their edges and also welded face-

wise to said semiseasoned celluloid; and said
elastic core being held under compression by
said celluloid shell.

ELEAZER KEMPSHALL.
